UNITED STATES PATENT OFFICE.

JOSEPH GRITTE, OF LYON, FRANCE, ASSIGNOR TO SOCIÉTÉ LYONNAISE DES RÉCHAUDS
CATALYTIQUES, SOCIÉTÉ ANONYME, OF RHÔNE, FRANCE.

CATALYTIC HEATING APPARATUS.

Application filed June 11, 1926, Serial No. 115,362, and in France June 8, 1925.

The catalytic heating apparatus used until this day, comprises one or more cylindrical wicks, having such a diameter that the intensity of distillation remains lower than the catalytic power of the catalytic agent. After a certain use, the upper part of the wick, impregnated with the residuents of the volatile liquid employed as fuel, and carbonized by the heat, forms a hard mass, preventing the supply of the fuel, by capillarity, near the catalytic heating unit. Consequently, the starting of the operation of the apparatus presents notable difficulties and likewise, an important reduction of the calorific power is observed, due to the insufficiency of distillation, thus producing often a disagreeable smell, because certain parts of the catalytic mass are not maintained at a temperature necessary to the production of the catalytic action.

Further, it occurs frequently that the wick, in consequence of a certain shrinkage of the absorbent material, such as cotton-wool, resulting from the successive moistenings with volatile liquid employed as fuel, ensures no longer suitable feeding, because its contact with the surrounding absorbent material is not sufficient.

The object of the present invention, is to provide a wick for catalytic heating apparatus, obviating the inconveniences mentioned above.

To this effect, a single wick is employed which is disposed in a hollow cylinder of large diameter mounted on a metallic net or armature with coarse meshes. Said armature bears at its upper end a fitting cap the border of which forms a screen protecting the upper edge of the wick against injurious heat. Said cap fits on a tube supporting the wick and presenting openings along its periphery. The heat reflected by the lower face of the catalytic body encounters therefore a large surface of the wick formed by the inner wall of the same. The distillation takes place on the whole of this surface which is thus not exposed to slow carbonization although it is at a great distance from the catalytic body.

According to a further object of the invention, the wick is constituted of two parts. The upper part, which after a long use is invaded by the residuents of the combustible fluid, is removable. It is fixed on the armature or metallic net by means of

catch buttons. The lower part is sewed on said armature and projects downwards.

At its lower end said part is cut longitudinally along a plurality of lines. The free projection; thus formed, are bent inwardly, in order to form a flat bottom for the wick and on this bottom a helicoidal spring bears which is disposed inside of the armature, for maintaining said bottom on a plate of swanskin or flannel, which is spaced from the bottom of the container by interposition of a layer of cotton-wool. Thus an intimate contact is ensured between the wick and the swanskin, and the latter is fed constantly by capillarity by means of the upper layers of absorbent material.

This invention is illustrated by way of example in the accompanying drawings, wherein:

Fig. 1 shows a sectional elevation of the catalytic heating apparatus according to the invention.

Fig. 2 is a partial sectional elevation showing the different parts forming the wick.

The cylindrical and hollow wick is constituted by two parts, one of these *a* being removable and the other *c* being fixed, said parts being connected to an armature or metallic net *d*, the first by means of catch buttons *b* while the second is sewed on the said first part. An enlargement *e* of the metallic net *d* indicates the suitable position of the removable part *a* which is protected against injurious heat of the catalytic body *f* by means of the cap *g*, fixed on the upper part of the armature *d* and fitted in the tube *h* bearing the wick, said tube presenting peripheral openings or perforations *h'*.

The fixed part *c* which is longer than the armature *d* is cut longitudinally at its projecting parts along a certain number of radial lines. The free projections, *i*, *j*, *k*, *l* thus formed, are bent inwardly, in order to form layers at the lower end of the wick. The lower end of the wick, constituted by said layers is maintained in contact with the plate of flannel or swanskin *m*, by means of a helicoidal spring *n*, which is arranged between said bottom and an annular restriction *o* of the armature *d*. The ring constituted by a thick plate of swanskin *m* has substantially the same diameter as the container *p* and rests on a first layer of absorbent material *q*, such as cotton-wool. On the ring *m* are disposed a plurality of layers

in cotton-wool *r* filling all the container and presenting a central opening for the passage of the wick. The volatile liquid employed as fuel is introduced in the opening *s* with filler neck *t*. The wick which passes through the absorbent material fits by its cap *g* in the form of a screen on the tube *h* carrying the wick. It is maintained in position by friction and the pressure produced by the catalytic body or heating unit *f*. The helicoidal spring *n* thus compressed acts under pressure between the flat bottom of the wick and the ring of swanskin *m* which absorbs by capillarity and by gravity the volatile liquid or fuel supplied constantly by the upper layers of cotton wool *r*. The feeding of the wick is thus permanently ensured.

In order to avoid the cooling of the peripheral part of the catalytic body *f*, a metallic ring *u* is soldered and then riveted, at the interior of the truncated cone, forming the upper part of the casing, said ring supporting the catalytic body. In this manner an annular chamber is formed, wherein the gases produced by the distillation of the fuel do not penetrate.

In order to distribute uniformly the combustible vapor contained in the vapor chamber on the entire surface of the catalytic body *f*, this latter presents a variable thickness, decreasing from the center toward the periphery.

A short tube *v* issues at the upper part of the vapor chamber and allows the introduction of a small quantity of fuel. A ring *x* formed by a thick sheet of asbestos surrounds the tube *h* bearing the wick and provided with openings, absorbs the fuel and the excess of the latter, passes through the opening of the tube, moistening the wick at its upper end. The introduction of the fuel before the operation of the apparatus accelerates the starting by presenting, in proximity of the catalytic heating unit, a reserve of fuel ready for distillation and further prevents that part of the wick not sufficiently moistened from being exposed at the action of heat, which would produce its carbonization.

50 What I claim as my invention, and desire to secure by Letters Patent is:

1. In a catalytic heating apparatus, a container, an absorbing material for fuel filling said container, a vapor chamber above said container, a hollow cylindrical wick disposed between said container and said chamber, an armature formed by a metallic net supporting said wick, a catalytic body covering said vapor chamber, said wick comprising two superposed parts, one removable and the other sewn on said armature and fed with

fuel principally at its base by projecting downwards in contact with said absorbing material.

2. In a catalytic heating apparatus, a container, an absorbing material for fuel filling said container, a vapor chamber above said container, a hollow cylindrical wick disposed between said container and said chamber, an armature formed by a metallic net supporting said wick, a catalytic body covering said vapor chamber, said wick comprising two superposed parts, one removable and the other sewn on said armature and projecting downwards, the lower end of said latter part being cut along a plurality of radial lines, the projections thus formed being bent inwardly in order to form a flat bottom for the wick, said bottom being in contact with said absorbing material.

3. In a catalytic heating apparatus, a container, an absorbing material for fuel filling said container, a vapor chamber above said container, a hollow cylindrical wick disposed between said container and said chamber, an armature formed by a metallic net supporting said wick, a catalytic body covering said vapor chamber, said wick comprising two superposed parts, one removable and the other sewn on said armature and projecting downwards, a flat bottom for said projecting part, a helicoidal spring disposed inside the armature for maintaining said bottom in contact with layers of material covering the base of said container and being in contact with the absorbing material.

4. In a catalytic heating apparatus, a container, an absorbing material for fuel filling said container, a vapor chamber above said container, a hollow cylindrical wick disposed between said container and said chamber, an armature formed by a metallic net supporting said wick, and a catalytic body covering said vapor chamber, the thickness of said catalytic body decreasing from the center to the periphery.

5. In a catalytic heating apparatus, a container, an absorbing material for fuel filling said container, a vapor chamber above said container, a hollow cylindrical wick disposed between said container and said chamber, an armature formed by a metallic net supporting said wick, a catalytic body covering said vapor chamber, a supplementary opening wherethrough fuel can be introduced in proximity to the catalytic body, said fuel, when starting the apparatus, moistening the upper part of the wick and also operating to preserve the latter by preventing carbonization thereof.

In witness whereof I affix my signature.
JOSEPH GRITTE.
